UNITED STATES PATENT OFFICE.

EDWIN A. RUTENBER, OF LOGANSPORT, INDIANA, ASSIGNOR TO THE RUTENBER ELECTRIC COMPANY, OF LOGANSPORT, INDIANA, A CORPORATION OF INDIANA.

ELECTRICAL CONNECTION FOR SAD-IRONS AND THE LIKE.

1,091,767.

Specification of Letters Patent. Patented Mar. 31, 1914.

Application filed December 10, 1912. Serial No. 735,831.

To all whom it may concern:

Be it known that I, EDWIN A. RUTENBER, a citizen of the United States, residing at Logansport, county of Cass, and State of Indiana, have invented a certain new and useful Electrical Connection for Sad-Irons and the like, of which the following is a specification.

This invention is an electrical connection 10 and a sad iron for use therewith, said connection being adapted for separably attaching a feed conductor to an apparatus of a suitable character for utilizing the energy of an electric current supplied by said conductor.

The object of the invention is to enable a conductor to be attached to, or disconnected from, the current-utilizing apparatus by the simple operation of slipping one member 20 into and out of coöperative relation to a second member, and at the same time to effectively insulate the metallic parts of said connection, thus simplifying and expediting the operations of connecting and disconnecting the conductor.

My electrical connection is useful, more particularly, as a means for attaching and detaching a conductor to an electrically heated sad iron, although it will be understood that its use is not restricted to a specified tool or apparatus, but in the example shown in the drawings, that member which is attached to the iron is so positioned that the posts are advantageously exposed for 35 convenient access to the member attached to the conductor.

The invention, in a preferred form of construction, embodies two members composed of insulating material, one member being 40 provided with a plurality of metal terminal posts which are partly incased by the member itself and which extend upwardly from said member so as to be exposed to easy access, whereas the second member is provided 45 with metal socket sleeves, each split or divided for a part of its length and threaded externally so that the sleeves are screwed into the material composing the member for the purpose of incasing said 50 sleeves by the member. The socket sleeves of the second named member are inserted into sockets which are separated by an intervening wall of insulating material to the end that said sleeves will become insulated 55 effectively, and said member is provided

with separated passages for the reception of the leading in wires which are in electrical engagement with said sleeves.

Other features of the invention, and the advantages thereof, will appear from the following detailed description taken in connection with the drawings.

In the accompanying drawings, I have illustrated one practical embodiment of the invention, but the construction shown there- 65 in is to be understood as illustrative, only, and not as defining the limits of the invention.

Figure 1 is a vertical section, partly in elevation, through an electrically heated sad 70 iron equipped with the separable connection of the present invention. Fig. 2 is a plan view with the top member and handle of the sad iron removed showing the bottom member, the electrical resistance therein, and 75 one member of the separable connection which is secured fixedly to the bottom member of the sad iron. Fig. 3 is an end view of the upper removable member of the separable connection. Fig. 4 is a vertical sec- 80 tion on an enlarged scale of the upper member of the separable connection.

The sad iron consists of two members A B, an electrical resistance C positioned within member A, a handle D of any suitable 85 form, and means, such as bolt E, for rigidly connecting the handle to the iron and members A B to each other.

Member A is composed of heat absorbing metal, or a composition of metals, said mem- 90 ber being preferably cast in one piece. Said member is provided in its upper face with a longitudinal channel *a* extending substantially parallel with the edges thereof, and within this channel is positioned the elec- 95 trical resistance C. Said resistance is a fine wire wound upon a core *c* composed of mica or other insulating material. The insulated wire wound upon the core is positioned within the channel of bottom member A, and this wire is insulated at *c'* from metallic contact with the metal of said bottom member, the insulation *c'* being at the bottom and at the respective side walls of channel *a*.

Member B is composed of a hollow cast- 105 ing, the edges of which are fitted firmly to member A, and the two members are assembled in accurate relation by dowel pins *b* of one member entering cooperating sockets of the other member. Member B is provided 110

with a chamber b' , and within this hollow member is confined heat resisting material F, such as one or more layers of asbestos, the edge portions of which enter a recess f provided in the edge of member B, whereby the heat resisting material F is clamped firmly in position between the two members so as to minimize the transmission of heat from member A into member B.

10 Handle D may be of any suitable or preferred construction, and it is positioned upon member B. Bolt E passes through the handle and member B, the lower part of the bolt being screwed into a threaded 15 socket provided in member A, whereby the single bolt operates to firmly clamp the handle to member B and to couple members A B together.

The separable connection consists of members G H, each composed of insulating material, one of said members (G) being secured fixedly in position to member A and inclosed within the chamber of hollow member B, whereas the other member H is removable at will in order to connect and disconnect conductor I. The member G is shown as consisting of a base portion g and an upwardly inclined portion g' , said base portion g being fashioned to rest firmly 25 upon the base member A of the sad iron. The member is secured firmly in position by screws g^2 which pass through suitable apertures in member G and enter threaded sockets provided in base member A. The up- 30 standing portion g' of socket member G is provided with inclined sockets g^3 , within which is partially incased the terminal posts J, two of which are employed. These posts are provided with screw-shaped lower heads 35 j , and said posts are externally threaded for a part of their length. Each post is inserted through the bottom of coupling member G before it is secured to base member A, so that the head j of the post will engage with 40 an internal shoulder of socket g^3 . On the threaded part of each post is screwed a clamping nut j' and a check nut j^2 , said nut j' coöperating with the head j in fixedly securing the post to socket member G. One 45 end of the resistance wire is electrically connected to one post J by the coöperating nuts $j' j^2$, whereas the other end of said resistance wire C is attached in a similar manner to the other post J by the nuts $j' j^2$ thereof, 50 as clearly shown in Fig. 2 of the drawings. The posts are thus secured firmly to, and partially incased by, the coupling member G in a manner to electrically insulate said posts from each other, and these posts are 55 provided with reduced end portions, the latter extending upwardly from the insulating member G and normally exposed to convenient access. The upstanding parts of the posts extend into the chamber of a thimble K, the latter being cast in a single piece 60

with the top member B and communicating with chamber b' thereof. The thimble serves as a housing for the upwardly extending part of posts J so as to prevent the latter from being struck or injured, but as the posts are positioned substantially centrally within the thimble they are adapted to readily enter the detachable member H of the coupling. As shown, the posts are inclined with respect to the horizontal plane 75 of base member A, and thimble K is inclined to top member B similarly to the inclination of posts J to base member A.

The removable coupling member H, shown more particularly in Figs. 3 and 4, 80 is provided with two sockets h separated by an intervening bridge wall h' . In addition to the sockets h , said member H is provided with longitudinal passages l, and at its upper part with a socket l', said passages 85 l being provided substantially in the web h' so that the passages l are separated from, or independent of, sockets h . The conductor I enters socket l' of coupling member H, and the wires i of this conductor are separated so as to extend through passages l, 90 said wires i being insulated from electrical contact with each other by the insulating material composing the web or wall h' of the member. 95

The sockets are enlarged at their outer ends to produce shoulders at h^2 , and within these sockets are positioned metal sleeves M, each sleeve having an enlarged screw head m the shoulder of which is adapted for abutting engagement with the shoulder h^2 within the socket. Each sleeve is threaded externally for a part of its length, and for the remainder of its length the sleeve is provided with longitudinal slits n, shown more 100 clearly in Fig. 4, whereby the end portion of the sleeve is made elastic so as to expand and secure good frictional contact with the posts. The threaded sleeve is screwed into the material of insulating member H for the 105 purpose of securing the sleeve fixedly in position within the member, said sleeve being substantially incased by the member and the two sleeves being electrically insulated by the web or wall h' . The wires i of conductor 110 I are extended from passages l into the sockets h, and the end portions of said wires are twisted around the respective sleeves so that the wires are clamped between the shoulders h^2 of member H and the heads m of sleeves 115 M, thereby securing good electrical contact of the wires with the sleeves. 120

When it is desired to connect the two members G H, member H is thrust into thimble K, which operation slides the sleeves 125 M over the exposed end portions of posts J. Member H is inserted into thimble K so as to be partly incased thereby, and the posts J enter the sleeves M so as to electrically connect the resistance coil, conductor I and 130

the posts. Current is adapted to flow through one conductor, the sleeve attached thereto, the post upon which the sleeve is mounted, thence through the resistance coil 5 and out through the other post, sleeve and conductor, whereby current is adapted to flow through the resistance coil so that the heat evolved will be communicated directly to the base member A of the sad iron.

- 10 It will be observed that member H can be easily pulled out of the thimble, as a result of which the sleeves are withdrawn from the posts, thus readily separating the two members of the coupling. For connecting conductor I to the said iron it is only necessary to insert member H into thimble K, whereupon the sleeves of said member H will engage frictionally with posts J, thereby connecting the resistance coil in circuit 15 with the conductor I.

Having thus fully described the invention, what I claim as new, and desire to secure by Letters Patent is:

1. An electrical connection of the kind 25 specified embodying a member composed of insulating material and provided with longitudinal sockets separated by an intervening wall and with wire passages separate from said sockets, a plurality of metal 30 sleeves positioned within the sockets and incased by the material of said member, said sleeves being in electrical engagement with leading in wires adapted to extend through said wire passages, a second member composed of insulating material, and metal posts 35 fixed to and partly incased by the second member, said metal posts projecting outwardly from the second member so as to be exposed for convenient engagement by the 40 metal sleeves of the first member.

2. An electrical connection of the kind 45 specified embodying a member composed of insulating material and provided with sockets, a plurality of posts partly incased by the sockets and clamped to said member,

said posts projecting outwardly from the member; a second member composed of insulating material and provided with sockets and with passages separate from said sockets, wires passing through said passages 50 in the second member, and sleeves incased within the sockets of the second member, said sleeves being electrically attached to the wires and having frictional engagement with the exposed parts of said posts. 55

3. An electrical connection of the kind specified embodying a member composed of insulating material and provided with sockets, a plurality of posts partly incased by the sockets and clamped to said member, 60 a second member composed of insulating material and provided with sockets, and threaded metal sleeves screwed into the sockets and incased within the material of the second member, said sleeves being split 65 for a part of their length and adapted for frictional engagement with said posts.

4. The combination with a two-part translating device, one part of which is chambered, and a resistance coil, of a thimble 70 extending upwardly from said chambered member, a coupling member composed of insulating material and secured fixedly to one part and, within the chambered part, a plurality of posts secured to said coupling member 75 and extending upwardly within the thimble, a second coupling member composed of insulating material and insertible into the thimble, a conductor attached to the second member, and a plurality of sleeves 80 secured to the second member and positioned for frictional engagement with said posts.

In testimony whereof I have signed my name to this specification in the presence of two subscribing witnesses.

EDWIN A. RUTENBER.
